(57) CLAIM

The ornamental design for a shoe as shown and described.

DESCRIPTION

FIG. 1 is a side view of a shoe showing my new design; FIG. 2 is a rear perspective view thereof;

FIG. 3 is a rear view thereof;

FIG. 4 is an opposite side rear perspective view thereof; and,

FIG. 5 is an opposite side view thereof.

The broken line immediately adjacent to the solid line defines the bounds of the claimed design and forms no part thereof. The broken lines and unshaded areas depicting the remainder of the shoe form no part of the claimed design.
